US00D915865S

(12) **United States Design Patent** (10) **Patent No.:** **US D915,865 S**
Choi et al. (45) **Date of Patent:** **** Apr. 13, 2021**

(54) **SMART KEY FOR CONSTRUCTION MACHINE**

(71) Applicant: **Doosan Infracore Co., Ltd.**, Incheon (KR)

(72) Inventors: **Seula Choi**, Incheon (KR); **Minki Kim**, Incheon (KR); **Yoojeung Lim**, Incheon (KR); **Sunwook Kwack**, Incheon (KR)

(73) Assignee: **DOOSAN INFRACORE CO., LTD.**, Incheon (KR)

(**) Term: **15 Years**

(21) Appl. No.: **29/693,669**

(22) Filed: **Jun. 4, 2019**

(30) **Foreign Application Priority Data**

Dec. 11, 2018 (KR) 30-2018-0058353

(51) **LOC (13) Cl.** **08-07**

(52) **U.S. Cl.**

USPC **D8/347**; D13/136

(58) **Field of Classification Search**

USPC ..... D8/349, 382-399, 342-345, 347, 348, D8/330, 331; D3/201, 208, 207; D13/167, 168, 171, 169, 123, 158 CPC A45F 5/021; A45F 2200/0558; A45F 5/02; G07C 2009/00984; G07C 9/00944; G07C 9/00; A44B 15/00; H04M 1/72541; H04M 1/6775; H04M 2250/10; H04W 76/50; G05G 1/02; B60R 25/00; G08B 25/08; H01M 2/1044; H01M 2/08; Y02E 60/10; A45C 11/32; A45C 13/008
